Primary Examiner — Paula Greene(74) *Attorney, Agent, or Firm* — Perkins Coie LLP(57) **CLAIM**

The ornamental design for an earphone, as shown and described.

DESCRIPTION

FIG. 1 is a left side isometric view of an embodiment of an earphone showing our new design;

FIG. 2 is a rear elevation view thereof;

FIG. 3 is a front elevation view thereof;

FIG. 4 is a top plan view thereof;

FIG. 5 is a bottom plan view thereof;

FIG. 6 is right side elevation view thereof; and,

FIG. 7 is a left side elevation view thereof.

The broken lines in the drawings represent environmental subject matter that forms no part of the claimed design.
